UNITED STATES PATENT OFFICE

AUGUST MERTES, OF CLEVELAND, OHIO, ASSIGNEE, BY MESNE ASSIGNMENTS, TO THE
PITTSBURGH PLATE GLASS COMPANY, OF PITTSBURGH, PENNSYLVANIA, A COR-
PORATION OF PENNSYLVANIA

AUTOMATICALLY ACTING BRUSH MAKING MACHINE

Application filed August 21, 1922, Serial No. 583,251. Renewed October 17, 1931.

My invention is particularly directed to the provision of a machine which shall automatically produce a completed brush by merely supplying proper materials to the machine. The various instrumentalities of the machine are so arranged as to operate in proper sequence to perform all of the operations necessary to completion of the product from the preparation of the backs of the brush by drilling suitable openings therein to the cutting and folding of wires that serve as the bristles of the brush. The advantages of such machine are manifest and it is not necessary to dwell upon the economic features thereof resulting from a completely automatic operation. The various features and operation of the machine will be clearly understood from an examination of the accompanying drawings in conjunction with the description thereof in which like numerals indicate corresponding parts.

Figure 1 is a side elevational view of a machine embodying the features of my invention; Fig. 2 is an elevational view of the reverse side of the machine shown in Fig. 1; Fig. 3 is an elevational view of one end of the machine upon a somewhat larger scale; Fig. 4 is an end elevation showing a wire folding mechanism and a feeding device for transversely disposed locking wires; Fig. 5 is a detail view of a wire cutting mechanism associated with the folding device; Fig. 6 is a fragmentary longitudinal sectional view of the machine illustrating a carrier actuating mechanism; Figs. 6a and 6b are detail views of members of the assembly shown in Fig. 6; Fig. 7 is a sectional view showing an assembly for manipulating a transversely disposed locking wire; Fig. 7a is a fragmentary plan view of the assembly shown in Fig. 7; Fig. 8 is a rear elevational view of mechanism for transferring a severed portion of wire to be utilized to anchor the wire bristles in position; Fig. 9 is a detail view of mechanism for disposing a transverse anchoring wire in position in a brush back; Fig. 10 is a side elevational view of gripping jaws operable to dispose wires in a cutting and folding mechanism; Fig. 11 is a front elevational view of the device shown in Fig. 10; Fig. 12

is a detail sectional view of another gripping device which cooperates to secure severance of wires to be disposed in a brush back; Fig. 13 is a fragmentary plan view of a carrier adapted to support brush backs in their progression through the machine; Fig. 14 is a longitudinal sectional view of the carrier shown in Fig. 13; Fig. 15 is a perspective view of a carrier member; Fig. 16 is a sectional view of mechanism for drilling brush backs vertically and horizontally; Fig. 16a is a sectional view of a driving gear arrangement for the drills shown in Fig. 16; Fig. 17 is a plan view of stationary folding plates; Fig. 18 is a front view of a device for folding wires and forcing them into vertically drilled openings in brush backs; Fig. 19 is a side view of the member shown in Fig. 18; Fig. 20 is a fragmentary sectional view of a brush back having looped wire bristles disposed in openings drilled to receive them; Fig. 21 is a side view of a cam mounted upon a main actuating shaft that controls the operation of the device for transferring the anchoring wires; Fig. 22 is a detail view of mechanism for transferring severed wires to be used as anchoring means for the main bristles; and Figs. 23 and 24 are respectively side and plan views of shifter jaws shown in Fig. 22.

The machine embodying my invention is assembled upon a frame 1 and utilizes a main actuating shaft 2 by means of which all of the various mechanisms are operated. Brush backs 3 formed of blocks of wood are moved in orderly progression through the machine by means of a conveyor comprising supporting members 4 pivotally linked together. Each supporting member is adapted to receive two brush backs 3 which are clamped in position between stationary plates 5 at the ends of the member and a centrally located wedge member 6. The wedge member is formed of a plurality of inclined plates 7 pivoted together, as indicated at 8, and a wedge plate 9 disposed upon a bolt 10 between the inclined plates whereby they may be forced into clamping position against brush backs placed upon the member 4. In order to maintain the several elements of the wedge member 6 in adjusted relation, 100

a leaf spring 11 is positioned between the inclined plates 7 beneath the wedge plate 9.

The conveyor is supported upon polygonal pulleys 12 mounted upon standards 13 at the ends of the machine. As shown in Fig. 6, means is provided for operating the conveyor which includes teeth 14 formed upon the bottoms of the members 4 that are engaged by a pawl 15 mounted upon a reciprocal bar 16. The bar is actuated by means of a link 17^a connected to a rock arm 17 pivotally mounted upon the frame, as indicated at 18. A pin 19 upon the arm 17 is engaged by a hook 20 fashioned upon an adjustable rod 21 pivotally connected to a rock arm 22 and is maintained in operative position by a spring 23 connected between the frame and the arm. The arm 22 is secured to a stub shaft 24 mounted upon the frame and an arm 25 carrying a roller 26 is likewise attached to the shaft 24. The roller engages a cam 27 fixed upon a shaft 28 which is rotated by a beveled gear 29 meshing with another beveled gear 30 secured to the main shaft 2. The cam 27 is provided with a recessed portion 31 which receives the roller 26 and consequently at regular intervals permits of a spring 32, connected to the frame and the arm 17, actuating the arm to cause the bar 16 and pawl 15 to be shifted in preparation for advancing the conveyor. Since there are necessarily spaces between the ends of the brush backs and the ends of the supporting members 4, provision must be made for advancing the conveyor a greater distance at periodic intervals than accomplished by the mechanism just described. To this end a ratchet wheel 33 is pivotally mounted upon the arm 17 and maintained in position by a spring 34. The wheel is provided with a number of uniformly cut teeth, depending upon the number of holes to be drilled in the brush backs and a recess of greater radial depth than the teeth. The wheel is rotated by a stationary rod 34^a secured to a bar 35 mounted upon the frame. When the spring 32 is permitted to move the arm 17 as the roller 26 enters the recess of the cam 27 the movement of the arm is limited by a fixed pawl 36 secured to a supporting member 37 attached to the frame. It will be apparent that greater movement of the arm 17, and consequently of the bar 16, will result when the ratchet wheel 33 is positioned to receive the pawl 36 in the recess.

The first operation that is performed upon the brush backs is to drill vertical holes therein to receive folded wires that constitute the brush bristles. The conveyor upon which the brush backs are mounted is advanced, as previously described, in a periodic manner to position the brush backs 3 beneath a drilling mechanism 38. The drilling mechanism includes a motor 39 having a gear wheel 40 meshing with a gear wheel 41 mounted upon a worm shaft 42 engaging

worm gears 43. Drill spindles 44 are connected by universal joints 45 to the worm gears and drive drills 46 mounted in a slideable block 47 disposed in guides 48 and adapted to be raised and lowered by a cam 49 upon the main shaft 2 through a connecting link 50. This mechanism drills vertical openings 51 in the brush backs 3 whereupon the backs are moved to a drilling mechanism that drills transverse openings to provide communicating passages for each row. A transverse drill 52 is mounted in a reciprocal shaft 53 that is reciprocated by means of a cam 54 likewise attached to the main shaft and connected to the shaft 53 by a bell crank 55. A small motor 56 is utilized to drive the shaft 53 by means of a belt 57 trained over a pulley 58 secured to the shaft.

After the brush backs are drilled to receive bristles which may be anchored in position by wires disposed in the transverse openings, they are advanced to a wire feeding, cutting and folding mechanism, indicated at 60. Flat wires 61 are assembled in superposed relation, two wires being utilized in the present instance, being drawn from a source of supply, not shown, in groups containing a number in parallel relation corresponding to the number of vertical openings drilled in the backs in a transverse row. The wires are drawn through guides 62 by alternately acting gripping members 63 and 64 (Fig. 3) which are longitudinally spaced, the one gripper 63 being mounted in fixed position but the other member 64 being supported upon a reciprocating bar 65. The bar 65 is reciprocated by means of a connecting arm 66 actuated by a cam 68 mounted upon the transverse shaft 28 through arms 69 and 70, a bell crank C and a link D, as shown in Figs. 1 and 6. The cam 68 is so designed as to give definite periods of movements to the bar and grippers, alternating with rest periods.

Intermediate of the grippers, a transverse rock arm 71, operated by a cam 72, shown in Fig. 5 and pivoted in the head at 72', is supplied with a cutter 73, which severs the wires in each row after they have been pulled forward by the action of the outer or first acting gripper 63, and when they are rigidly held by the inner gripper 64, which is the second gripper in order to act. A fixed abutment 74 serves to form the other element of the shears thus constructed.

After portions of the wires or sets of wires are severed in this manner, they are folded by means of a vertical plunger 75, having a spring-pressed plate 106 movably attached thereto. The plate is provided with marginal teeth 76, which force the severed wires between opposed projections 77 and 78, upon adjacent edges of opposed plates thereby to fold them prior to inserting them in the openings in the brush backs. This plunger is operated by means of a cam 107 secured to

the main shaft acting by the agency of a rock arm 108 and links 109 and 110, connected thereto (Figs. 5, 12, 18 and 20). A 5 depressible follower 79, which is adapted to prevent the ends of the wire loops from spreading after they leave the supports 77 and 78, is provided with an elongate opening therein, the sides of which are provided with marginal recesses 84 through which the teeth 10 of the plunger pass. The follower is mounted upon a swinging arm 81, pivoted at 82, and a spring 83 returns the arm to its normal position.

The grippers 63 and 64 are provided with 15 jaws 85 and 86 respectively. The wire feeding gripper 63 shown in Figs. 10 and 11 is the first to act and the movable jaw 86 is pivoted, as indicated at 93, and is provided with an 20 engaging part 94 adjustable by means of a set screw 95. This jaw is secured to the reciprocating bar 65. The jaw faces are preferably corrugated to assure positive engagement with the wires. A similar toggle, composed of plates 96 and 97, is operated by a depend- 25 ing arm 98 secured to the toggle plate 97. A spring 99 engaging a nut 100 of a bolt 101 serves to maintain the toggle plates in position when they are inoperative. The movable jaw 85 of the gripping member 64, particu- 30 larly shown in Fig. 12, is adjustable in guides 87 by means of set screws 88. A toggle composed of plates 89 and 90 placed edge to edge actuates the jaw by means of an operating arm 91, to which the lower plate 90 is attached. Guide plates E for the wires are attached to the guide frame.

When the wires are fed through the gripper 64 to the gripper 63, the jaws thereof must be positioned at a common level, but when the 40 wires are severed, the gripper 64 will drop slightly to permit the wires to lie upon the abutment 74 where they are cut. To permit this action, the guide frame 87 will fall by gravity, but in order to raise it again so that 45 the wires will be fed in alignment with the gripper 63, an adjustable screw 103 underneath the guide frame 87 is engaged by a rock arm 104 and the cam which operates the cutter is raised again to a normal level (Fig. 5). 50 A link 105 connected to the cutting arm, lowers this screw or pin to permit the guide frame to fall when the cutter fails. The wires 61 pass through a swinging guide 300, pivoted at 301 (Fig. 12), upon the vertically 55 movable frame 87 which holds the end of the wire after it has been cut off. This swinging guide is also engaged by the reciprocating gripper 63 when it advances to seize the projecting wire end, and is returned automatically 60 to its normal position.

A device for alternately operating the grippers is provided by utilizing a longitudinal sliding rod 200 reciprocated by means of a rock arm 201 which is actuated by the cam 65 68 (Figs. 1 and 3). A striker 202 engages

the arm 98 to operate the first gripper, as it moves forward and subsequently a striker 203 is caused to engage the arm 91 of the second gripper whereby the brush wires are secured in place while the first gripper returns for 70 another hold.

In Figs. 4, 7, 8 and 9 is shown the construction of a mechanism for feeding transverse wires 111 to the transverse openings in the brush backs. A guiding device is employed 75 which includes a rotatable frame 112 having an opening 113 into which screws 114 project. The wire is guided through cylindrical sleeves 115 rotatable with said frame operated by means of a pulley 116 and it is 80 straightened by passing over the ends of the screws 114.

In Figs. 7 and 7a, a wire feeding and cutting device for the transverse wires 111 is 85 shown. The device embodies toggle arms 117 pivoted upon a central shaft 118. One of the arms is pivoted upon a sliding head 120 and the other arm is pivoted upon a rock arm 119 which is pivoted upon the head. The wire 111 is directed through a guide 90 opening X in the toggle shaft 118 and through a guide opening Y in the head to combined cutting and gripping jaws 124 and 125. A set screw 141, adjustable in the rock arm 119, engages the movable jaw 124. 95

A cam 140 on the main shaft 2 engages a disc 122 upon the toggle shaft 118 and presses against the toggle, thus closing the jaws together and feeding the head and wire forward on a guide 121 until the head engages an 100 adjustable screw 123, whereupon the forward movement of the head is arrested. Further movement of the cam causes spreading of the toggle members thereby forcing the movable jaw 124 more firmly toward the stationary 105 jaw, thus severing the wire. A shoulder R upon the head 60 determines the length of the wire to be cut. A spring S upon a rod or pin T, which passes through the rock arm, releases the pressure upon the upper jaw from 110 the rock arm and screw 141. A spring 127 returns the head to its starting position which is determined by an adjustable rod 128.

The severed portion of the wire is inserted 115 between jaws 129 and 130 of a shifter, which receive the severed portion or nail from the gripping head, and transfer it to a position in alignment with the desired transverse opening in the brush back, or in alignment with the vertical openings last supplied with 120 looped wires, as shown in Fig. 8. The jaws 129 and 130 are yieldably retained in clamping relation by means of a spring 200 and are adapted to be separated by a member 201 when it engages the frame 60 over a bed 145 125 upon which the wire is deposited. The jaws are mounted upon an arm 131 pivoted upon the bed plate, as indicated at 132, and is operated to transfer the severed wire from one position to the other by means of a cam 133 130

(Fig. 4) on the main shaft. The cam engages a swinging arm 134 movably supported in a guide 135 on the frame 60. The arm is operatively connected to the shifter arm by means of the links 136, 137 and 138, and a bell crank 139, pivoted on the frame 60, as indicated at P. A screw 142 limits the rearward movement of the shifter arm, and a spring 143 (Fig. 4) returns it to position to receive a severed wire portion.

After the severed wire has been placed in its bed 145, a spring-pressed keeper plate 146 is moved to retain the wire in its bed until a plunger 147, operated by means of a cam 148 on the main shaft through the agency of a swinging arm 149 and link 150, forces the severed wire into the block. To permit of this action, the keeper plate 146 is raised by means of a spring pressed swinging plate 151, pivoted at 152 and a rod 153, which passes through an eye 154 on the swinging plate and is pivotally attached to the swinging arm 149 (Fig. 9). Rearward movement of the arm 149 raises the keeper plate, and forward movement thereof depresses the plate. A link 155 secured to a rock arm 156 pivotally attached to a weight 157 serve to return the plunger to an inoperative position. A spring 158 mounted upon the extremity of the plunger strikes against a shoulder 159 upon the frame and prevents concussion of the parts.

The operation of the various features of the machine will be apparent from the foregoing description, but the sequence of operation may be described as follows:

The wooden brush backs are secured one at a time at the front of the machine upon the conveyor mounted upon the rotatable supports 12 at each end thereof. The backs are operated upon first by the vertical drills 46 at the rear of the machine, where the vertical holes are made that receive the wire loops forming the bristles. The horizontal drill 52 then functions to form a communicating passage through each transverse row of openings in the backs wherein the locking wire or nail 111 is subsequently disposed. Thence each brush back is fed in turn to the filling position underneath the head 60, as shown in Fig. 3. Meanwhile parallel bands of wire 61 are fed periodically by means of reciprocating gripping jaws 63 to the knife cutter 73. Immediately the jaws 64 close upon the wires at a position rearwardly spaced from the knife thereby securing the wires in position until the knife descends and severs the wires.

At once the plunger, composed of members 75 and 106, descends and folds the several wires centrally between their ends and forces the resulting loops through the depressible guide follower 79. This follower is depressed with the loop and serves to prevent the ends of the severed wires from spreading after leaving the supports 77 and 78 upon

which they rest at their ends. After the loops have been pressed into the openings in the brush backs, transverse wires 111, cut to proper length by the knives 124 and 125, are then employed to fill the transverse openings in the brushes by means of the toggle mechanism shown in Figs. 7 and 8. The severed portion of the wire is seized between the jaws 129 and 130 of the shifting device, which transfers it to a position in alignment with a row of vertical openings in the brush back. A keeper plate 146 is utilized to retain the wire in position until the plunger 147 functions to insert the severed wire into the transverse opening in the back, and in this manner lock the wire loops therein. The conveyor is periodically moved to bring each brush back in turn underneath the plunger and the several cams are so timed as to cause the several mechanisms to be operated at the proper moment.

What I claim is:

1. A brush making machine comprising means for providing openings in brush backs to receive bristles, means for making communicating openings to receiving anchoring devices, means for folding and disposing wires in the first mentioned openings, and means for arranging anchoring devices in the communicating openings.

2. A brush making machine comprising a conveyor adapted to support a plurality of brush backs, means for drilling vertical openings in the backs, means for drilling transverse openings in the backs, means for folding and disposing wires in the vertical openings, and means for arranging anchoring devices in the transverse openings.

3. A brush making machine comprising a conveyor adapted to support a plurality of brush backs, means for actuating the conveyor at intervals, means for simultaneously drilling a plurality of vertical openings in the backs, means for drilling transverse openings to form communicating passages for the vertical openings, means for feeding and cutting wires to a predetermined length, means for disposing such wires in the vertical openings, and means for arranging anchoring wires in the communicating passages.

4. A brush making machine comprising a conveyor adapted to support a plurality of brush backs, means for actuating the conveyor at intervals, means for simultaneously drilling a plurality of vertical openings in the backs synchronously adjusted with the conveyor, means for drilling transverse communicating passages for the vertical openings, means for feeding and cutting wires to a predetermined length, means for disposing such wires in the vertical openings, means for feeding and cutting wires for anchoring the wires in the vertical openings and means for arranging the anchoring wires in position.

5. In a machine for the purposes described, a bed plate, a carrier for a multiple number of brush backs, intermittently acting means for propelling said carrier and brush backs over said bed plate, means for successively drilling spaced transverse rows of vertical openings in said brush backs, means for drilling spaced transverse openings connecting the openings in each transverse row 5 of openings, gripping means for feeding parallel wires over said frame, gripping means acting alternately therewith for retaining said wires in their extended positions, means for severing portions at the outer extremities 10 of said wires, plunger means for looping said severed portions, said plunger serving also for driving the same into the openings in one of said transverse rows of openings. 15
6. In a machine for the purpose described, 20 a bed plate, a carrier for a multiple number of spaced brush backs, intermittently acting means for propelling said carrier and brush backs over said bed plate, means for successively drilling spaced transverse rows of vertical openings in said brush backs, means 25 for drilling transverse openings connecting the openings in each transverse row of openings, gripping means for feeding parallel wires over said frame, gripping means acting alternately therewith for retaining said wires in their extended positions, means for 30 severing portions at the outer extremities of said wires, plunger means for looping said severed portions, said plunger means serving for driving said looped portions into the 35 openings in one of said transverse rows of openings, and a follower adapted to prevent the extremities of said looped portions from spreading until they are deposited in said 40 row of openings.
7. In a machine for attaching brush wires to a multiple number of brush backs, a brush back carrier composed of sections arranged in alignment with each other, a rack secured 45 to each section, means for flexibly connecting said sections together, and means secured to said sections for detachably securing brush backs thereto. 50
8. In an endless carrier for propelling a number of brush backs, a multiple number of spaced sections, terminal and intermediate attaching means upon said sections for said brush backs, and rack portions upon said sections, said rack portions being spaced at positions corresponding with the spaces between the brush backs upon said sections. 55
9. In a machine for the purpose described, an endless carrier for a multiple number of brush backs composed of a multiple number of spaced sections hinged together, spaced 60 rack portions on the sections opposed to the brush backs, a reciprocal pawl in the machine engageable in turn with the racks, means for reciprocating the pawl intermittently to propel the carrier, and mechanism in said re-
- ciprocating means for periodically increasing the amount of movement of the pawl to propel the carrier over the spaces between the carrier sections, and between the spaced brush back thereon. 70
10. In a device for the purpose set forth, an endless carrier composed of spaced sections hinged together, a retaining means at each end thereof for brush backs, intermediate movable retaining means adapted to 75 secure the brush backs in engagement with the end retaining means and means for spreading said intermediate retaining means and for securing them in place. 80
11. In an endless carrier adapted to propel a multiple number of brush backs, said carrier being composed of sections hinged together, a retainer for brush backs at each end of each section, and intermediate adjustable retaining means for said brush backs. 85
12. In a machine for manufacturing wire brushes, a frame, a fixed jaw thereon, a co-acting cutting blade, a pair of gripping jaws, positioned adjacent one side of said fixed jaw and adapted alternately to engage and 90 release flexible brush wires and to pull them to a cutting position, a pair of gripping jaws adjacent the other side of said fixed jaw, and adapted to hold said wires in position while operated upon by said cutting blade, means for reciprocating the pulling jaws, and means for alternately closing and opening the pulling jaws coincidently with the opening and closing of the holding jaws. 95
13. In a wire cutting and folding device 100 for the purpose set forth, the combination with spaced gripping means, of an intermediate cutting device, spaced supports for the wires when severed by the cutting device, said spaced supports having opposed teeth projecting therefrom towards each other, and a plunger provided with teeth adapted to enter the openings between the teeth of said supports and to force the severed wires therebetween. 105
14. In a machine for the purpose set forth, opposed wire supports, having toothed adjacent extremities, a plunger provided with teeth upon its extremity adapted to fold and force the folded wire between the teeth in said supports, and a follower adapted to encircle said folded wires as they are forced through said supports, and a depressible support for said follower. 110
15. In a wire propelling and cutting device 115 for the purpose set forth, an oscillating arm, a releasable holding means upon the extremity of said arm into which a severed wire is inserted, and from which it is automatically deposited, and propelling means for said severed wire. 120
16. In a machine of the character described, the combination with a support, of a stationary holding device mounted thereon, a pulling device movable towards and from said holding device, and an intermediate cut- 125 130

ting device adjacent to said holding device.
17. In a machine of the character described, the combination with a support, of a stationary holding device mounted thereon, a pulling device movable towards and from said holding device, and an intermediate cutting device adjacent said holding device, and means for operating said holding device to seize and hold a strand while cut by said cutting device, and means for simultaneously operating said cutting device.

10 In testimony whereof, I hereunto set my hand this 21st day of July, 1922.

AUGUST MERTES.
